UNITED STATES PATENT OFFICE.

GEORGE W. HARRIS, OF HOBART, OKLAHOMA.

TOOL-HANDLE.

1,184,449.

Specification of Letters Patent. Patented May 23, 1916.

Application filed October 21, 1915. Serial No. 57,151.

To all whom it may concern:

Be it known that I, GEORGE W. HARRIS, a citizen of the United States, residing at Hobart, in the county of Kiowa and State of Oklahoma, have invented certain new and useful Improvements in Tool-Handles, of which the following is a specification.

This invention relates to tool handles and more particularly to a handle which is especially adapted for use in connection with planes although the novel features of construction embodied in the present invention may be employed in a handle designed especially for use in connection with various other kinds of tools as, for example, saws and the like.

It is the aim of the invention to so construct the handle that it will readily conform to the shape of the hand when closed about the handle, thereby rendering the tool to which the handle is applied, more convenient and less fatiguing to handle.

Another aim of the invention is to so form the grip portion of the handle that it will constitute an effective abutment for the heel of the palm of the hand so that considerable force may be exerted against the handle in the use of the tool without tiring the hand to the same extent as where the ordinary form of handle is employed.

In the accompanying drawings: Figure 1 is a perspective view of a plane provided with a handle formed in accordance with the present invention. Fig. 2 is a side elevation of the handle. Fig. 3 is a rear elevation thereof. Fig. 4 is a horizontal sectional view on the line 4—4 of Fig. 2. Fig. 5 is a diagonal section on the line 5—5 of Fig. 2. Fig. 6 is a view similar to Fig. 5, taken on the line 6—6 of Fig. 2.

In the drawings the numeral 1 indicates in general a tool such, for example, as a plane and as aside from the handle the tool is of the ordinary construction, further description thereof is deemed unnecessary.

The handle embodying the present invention includes an attaching base and a grip portion, the base portion being indicated in general by the numeral 2 and having a forward extension 3 provided with an opening 4 through which may be fitted a securing screw or the like indicated by the numeral 5, which screw enters the body of the plane 1 and constitutes a means for securing the handle to the said body. A relatively long bolt is to be fitted through a bore

7 extending longitudinally through the handle and this bolt constitutes a means for securing the handle in place.

Generally speaking, the grip portion of the handle, indicated by the numeral 8, is curved upwardly and forwardly from the attaching base 2 of the handle and its upper surface is convex from its forward to its rear end, the grip at its upper end and at its rear side being provided with a rearwardly extending nose 9, the upper face of which constitutes a continuation of the upper face of the grip proper. The under surface of the nose 9 is transversely and longitudinally convex so as to fit snugly within the hollow of the hand between the base of the thumb and forefinger. At a point immediately below the nose 9 the grip of the handle is elliptical in cross section as clearly shown in Fig. 6 of the drawings, this portion being indicated specifically by the numeral 10. Below the portion 10 the handle is provided at its under side and at its rear with a wing 11 which projects laterally and rearwardly from the body portion of the grip and the lateral or forward side of which, indicated by the numeral 12, constitutes a continuation of the lateral face of the lower portion of the said body of the grip, the merging surfaces being concave so as to form a concave seat for the tips of the middle, third and little fingers of the right hand when the handle is grasped. The outer or lateral edge of the wing 11 extends along a curved line 13 gradually receding from the plane of the body portion of the grip and extends from the portion 6 to the attaching base 2, this edge at its lower end terminating at the rear side or edge of the said base and at the plane of the bottom of the said base. The wing 11 constitutes an abutment for the heel of the palm of the hand, as before stated, and in order that the heel of the palm may comfortably seat against the said wing, that face of the wing opposite the face 12 is of anti-clastic form, this face being indicated by the numeral 13. As will be apparent by reference to Figs. 4 and 5 of the drawings, the face 13 is transversely convex and terminates at one side at the outer edge of the wing and at its other side merges with the surface of the body of the grip at the righthand side thereof. The face 13 is concave from its upper to its lower end, the body of the grip portion being, however, convex as indicated at 14, between the upper

110

end of the outer edge of the wing and the upper end of the concave surface 13.

From the foregoing description of the invention it will be apparent that the grip of the handle is of such contour that it will snugly conform to the hand when grasped and that due to the provision of the wing 11 and the peculiar formation of its forward and rear faces, the wing constitutes an effective abutment for the heel of the palm of the hand, thereby permitting of the application of considerable force against the handle without, however, tiring the user of the tool to the same extent as when a handle of the ordinary form is employed.

Having thus described the invention, what is claimed as new is:

- 20 1. A tool handle having a grip portion provided with a lateral wing constituting an abutment for the heel of the palm of the hand, the forward face of the wing being transversely concave to form a seat for the tips of the fingers when the handle is grasped.
- 25 2. A tool handle having a grip portion provided with a lateral wing constituting an abutment for the heel of the palm of the hand, the forward face of the wing being transversely concave and merging with the adjacent lateral face of the body of the grip

portion, and the rear face of the wing being transversely convex and merging with the other lateral face of the said grip portion, the said rear face of the wing being longitudinally concave.

3. A tool handle comprising a grip portion curved in a general upward and forward direction and having its forward side longitudinally concave and transversely convex, the rear face of the said body near the lower end thereof being substantially obliquely disposed, the said grip portion being formed at one side and at the rear with a laterally projecting wing longitudinally concave and transversely convex at its rear side and having its said rear side merging with the rear side of the said grip portion, the forward side of the said wing being transversely concave and merging with the adjacent lateral face of the said grip portion, the upper portion of the wing being gradually decreased in width until it merges into the surface of the rear and said lateral face of the grip portion.

In testimony whereof I affix my signature in presence of two witnesses.

GEO. W. HARRIS. [L.S.]
